Primary Examiner — Lilyana Bekic*Assistant Examiner* — Mary Shannon Malley(74) *Attorney, Agent, or Firm* — Thomas Coester Intellectual Property(57) **CLAIM**

The ornamental design for a spa pool, as shown and described.

DESCRIPTION

FIG. 1 is a front perspective view of a spa pool in accordance with the design.

FIG. 2 is a rear perspective view of the spa pool.

FIG. 3 is a front view of the spa pool.

FIG. 4 is a rear view of the spa pool.

FIG. 5 is a left view of the spa pool.

FIG. 6 is a right view of the spa pool.

FIG. 7 is a top view of the spa pool.

FIG. 8 is a bottom view of the spa pool.

FIG. 9 is a cross-sectional view of the spa pool along line 9-9.

FIG. 10 is a cross-sectional view of the spa pool along line 10-10.

FIG. 11 is a cross-sectional view of the spa pool along line 11-11; and,

FIG. 12 is a cross-sectional view of the spa pool along line 12-12.

The broken lines depict portions of the spa pool that form no part of the claimed design.
